UNITED STATES PATENT OFFICE.

WILLIAM L. DENIO, OF ROCHESTER, NEW YORK, ASSIGNOR OF ONE-HALF
TO HOBART F. ATKINSON, OF ROCHESTER, NEW YORK.

TELEPHONE.

SPECIFICATION forming part of Letters Patent No. 728,162, dated May 12, 1903.

Application filed February 6, 1903. Serial No. 142,115. (No model.)

To all whom it may concern:

Be it known that I, WILLIAM L. DENIO, a citizen of the United States, residing at Rochester, in the State of New York, have invented
5 an Improvement in Telephones, of which the following is a specification, reference being had to the accompanying drawings.

My invention relates to an improvement in telephones, the object of which is to increase
10 the sensibility and power of the instrument.

My improvements are fully described and illustrated in the following specification and the accompanying drawings, the novel features thereof being specified in the claims annexed to the said specification.

In the accompanying drawings, Figure 1 is a section of a telephone-receiver. Fig. 2 is a plan view of the washer or gasket. Fig. 3 is a side view of the washer or gasket. Figs.
15 4, 5, and 6 represent modifications.

In Fig. 1, A is the case of an ordinary telephonic receiver. The threaded cap B screws onto the end of the case A, holding the diaphragm C around the edge of its periphery
20 between the corrugated washer or gasket D and the cap B. E is a magnet, attached to the ends of which are the coils F, which cause the diaphragm to vibrate when the instrument is in operation.

Between the receiver-case A and the diaphragm C is placed the washer D, which is preferably made of sheet metal bent or corrugated, as shown in Figs. 2 and 3. The result of the corrugations is to hold the diaphragm firmly, so that it cannot rattle, but at the same time to allow the diaphragm to vibrate much more freely than it would if held rigidly, as in the ordinary receiver, thereby
35 much increasing the sensitiveness of the instrument and the strength of the sound emitted by it. In the ordinary telephone the diaphragm is held tightly between the case and the cap, which restricts its vibration, or if the diaphragm is not held tightly it rattles; but

40 where my invention is employed the diaphragm is held firmly, preventing it from rattling, but at the same time leaving it so it can vibrate freely, thereby making a very sensitive instrument and preventing the metallic

tone frequently observed. The threaded cap 50 B provides an easy means of adjusting the tension of the diaphragm so as to obtain the best results.

My improvement may be applied to telephones, phonographs, or any acoustic instrument having a vibrating diaphragm. I have observed that the clearest tones and the greatest volume of sound are secured when the diaphragm is resiliently supported at an even number of points around its periphery.

60 The corrugated washer may be made of any suitable metal or alloy—such as aluminium, brass, iron, or steel—although I prefer to employ the same material as in the diaphragm. I have also used washers of celluloid, hard 65 rubber, paper, and fiber. As indicated in the drawings, the washer is placed on the same side of the diaphragm as the magnet, and I prefer to use it in such location; but it may be placed on the other side, or two washers may be used, one on each side of the diaphragm. I have also employed a concaved washer, such as indicated in Figs. 4 and 5, which may be divided or cut away to form independent bearing-points, as represented 75 in Fig. 6.

I claim—

1. In a telephone or other acoustic instrument having a vibrating diaphragm, the combination with the diaphragm of the corrugated washer the magnet and the supporting-case, substantially as described.

2. In a telephone or other acoustic instrument having a vibrating diaphragm, the combination with the diaphragm of the corrugated washer and the cap provided with means for adjusting the tension of the diaphragm, substantially as described.

3. In a telephone or other acoustic instrument having a vibrating diaphragm, the combination with a frame or case, of the diaphragm, the corrugated washer and the cap, substantially as described.

WILLIAM L. DENIO.
